US0D1061096S

(12) **United States Design Patent** (10) Patent No.: **US D1,061,096 S**
(45) Date of Patent: ** Feb. 11, 2025

(54) **BODY FOR SHOE MANAGEMENT APPARATUS**

(71) Applicant: **LG ELECTRONICS INC.**, Seoul (KR)

(72) Inventors: **Jaeyoung Kim**, Seoul (KR); **Bohyun Nam**, Seoul (KR); **Seunghyun Song**, Seoul (KR)

(73) Assignee: **LG ELECTRONICS INC.**, Seoul (KR)

(**) Term: **15 Years**

(21) Appl. No.: **29/842,933**

(22) Filed: **Jun. 16, 2022**

(30) **Foreign Application Priority Data**

Dec. 17, 2021 (KR) 30-2021-0060957

(51) LOC (15) Cl. **06-04**

(52) U.S. Cl.

USPC **D6/675.1**; D32/8

(58) **Field of Classification Search**

USPC D6/663, 668.1, 672, 675, 675.1, 675.2, D6/675.4, 675.5, 680.2, 683, 683.1;

D32/2, 6, 8

CPC A47B 47/03; A47B 47/021; A47L 23/00; A47L 23/02; A47L 23/20; A47L 23/205

(57) **CLAIM**

The ornamental design for a body for shoe management apparatus as shown and described.

DESCRIPTION

FIG. 1 is a front perspective view of the body for shoe management apparatus showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a front perspective view showing the state of use that shoes have been placed inside of the claimed design. The broken lines depict portions of the body for shoe management apparatus that form no part of the claimed design. The shoes of FIG. 8 drawn in broken lines show environmental structure only and form no part of the claimed design.

1 Claim, 8 Drawing Sheets
